Elemir J. Ney, of Lowell, Mass.
assignor to Lowell Manufacturing Company, of Lowell.
Letters Patent No. 1175, dated Dec. 20, 1859.

The schedule referred to in these Letters Patent and making part of the same.

To all whom it may concern:

Be it known that I, Elemir J. Ney, of Lowell, in the County of Middlesex and State of Massachusetts, have originated and designed a new pattern for Carpets or other fabrics, of which the following is a full, clear and exact description reference being had to the accompanying drawings, making part of this specification.

1. 2. 3 & 4 in the corners when matched form an Octagon figure bordered with small balls and surrounded by a plain frame. C. D. E. & F. are octagons similar to that of the corners.

Lying between and partly under the Octagons are the leaves 5, each of which support a rosette 6.

Figs. 7 & 8 at the sides when matched form a plain cross surrounded by a scalloped band 7.

Figs. 8 & 9 when matched form a figure similar to the one formed by matching Figs. at the sides.

The remaining portions of the design are covered with small sprigs.

The colors employed in the different portions of the design may be varied to suit the taste and wish of the manufacturer.
